UNITED STATES PATENT OFFICE.

SUNKER ABAJI BISEY, OF NEW YORK, N. Y.

ROWING MECHANISM.

Application filed February 25, 1920. Serial No. 361,154.

To all whom it may concern:

Be it known that I, SUNKER ABAJI BISEY, a subject of the King of Great Britain, and a resident of New York city, county and 5 State of New York, have invented certain new and useful Improvements in Rowing Mechanism, of which the following is a specification.

My present invention relates to the 10 propulsion of small boats and the objects of the invention are to combine in a single, practical and simple structure the efficient features of a propeller or paddle wheel drive and the advantages of the exercise usually 15 afforded by rowing.

Another object is to enable the operator to face forward and to easily control the boat at will.

The invention involves a number of novel 20 features of construction, combinations and arrangements of parts, all of which will appear in the course of the following specification.

The drawing accompanying and forming 25 a part hereof illustrates the invention embodied in but two of its practical forms, but it will be understood that modifications may be made without departure from the true spirit and scope of the invention as 30 defined herein.

In the drawing Figure 1 is a top plan view of a boat equipped with my improved 35 rowing mechanism.

Figure 2 is a broken side elevation of the 40 same.

Figure 3 is a transverse sectional view on substantially the plane of line 3-3 of Figure 2.

Figure 4 is a transverse sectional view and 45 Figure 5 is a broken longitudinal sectional view of a modified paddle wheel construction.

The mechanism is illustrated as applied 50 to a boat 7 having athwartship seats 8, the forward one of which is to be occupied by the operator.

In the first construction illustrated the boat is driven by a propeller or propelling wheel 9 carried by a longitudinal shaft 10.

55 The rowing mechanism consists in the illustration of a swinging fork or yoke 11 pivotally supported on the transverse shaft 12 and carrying at its upper end the reversely facing handles 13. This oscillating handle mechanism is connected with the

propeller shaft by suitable gearing, the same being herein shown as comprising a pawl 14 pivoted between the sides of the fork and engaging a ratchet wheel 15 fast on the transverse shaft, said transverse 60 shaft carrying a mitre gear 16 in mesh with a mitre pinion 17 on the propeller shaft. The propeller shaft may carry a fly-wheel 18 for maintaining the propelling operation as nearly continuous as possible. 65

The rowing operation is simulated by causing the handles to yield and to move laterally in the same fashion as the handles of the oars in ordinary rowing. For this purpose the handles are shown as provided 70 with shank portions 19 pivoted at 20 at opposite sides of the upper end portion of the yoke and as yieldingly forced apart by the spring 21. The approaching and separating movements of the handles may 75 be limited by properly positioned stops, such as indicated at 22 and 23. The pivots 20 are arranged as indicated so as to permit the handles to yield only in a lateral direction. 80

In using this construction the operator faces forward and propels the boat by a simple rowing movement, the handles having a tendency to spread on the forward stroke and to contract or come together 85 on the rearward power-applying movement. On the forward or idle stroke the pressure on the handles is relatively light and the spring 21 is of sufficient force to thrust the handles apart so that at the commencement of the rearward or active stroke the handles are in their spread apart relation (Figure 3) but come together, as in Figure 1, due to the straight line pull being applied. This, therefore, gives all the healthful 90 exercise ordinarily found in rowing, but without the disadvantages ordinarily accompanying such exercise. The boat can be held under proper control at all times and be driven faster or slower as desired. 100

Steering may be accomplished by means of a foot bar 24 pivoted at 25 and connected by tiller ropes 26 with the rudder.

In order that the operator may reverse 105 the boat at will, I prefer to make the one-way drive connection reversible as by pivoting the pawl at 27 so that it may be swung to face in either direction and by providing the ratchet wheel with teeth which will be effectively engaged by the pawl in either 110

relation. The pawl may be provided with a handle such as indicated at 28 so that it may be quickly swung over from one position to the other when manipulating the 5 boat in close quarters.

The propelling may be accomplished by means of a propelling or paddle wheel which is indicated at 30 in Figures 4 and 5 in which event the paddle wheel might be 10 carried by a shaft 31 and might operate within a well 32 provided in the bottom of the boat, the paddle wheel shaft being directly connected by gears 33, 36, with the ratchet shaft 34. In this construction I 15 have shown two ratchets 35 disposed at opposite sides of the drive gear 36 and arranged to be engaged by two pawls or the two tongues of a single pawl 37 mounted on the fork and arranged to straddle the 20 drive gear, such construction giving a balanced drive.

The invention, it will be seen, is simple and can be readily applied and gives the full effectiveness of a wheel drive with all 25 the beneficial and usually more or less leisurely exercise afforded by rowing.

What I claim is:

1. Rowing mechanism for boats comprising in combination with a propelling wheel 30 and a ratchet wheel geared thereto, a swinging yoke, a pawl carried by said yoke and engaging the ratchet wheel, handles mounted on said yoke and yieldable laterally in simulation of the spreading movement of 35 a pair of oars, said handles having shank portions pivoted on the yoke and spring mechanism for yieldably forcing said handles away from each other.

2. Rowing mechanism for boats comprising 40 in combination, a propelling wheel, rowing handles pivoted to swing longitudinally of the boat, drive gearing for transforming the oscillatory movement of the rowing handles into rotary movement at the 45 propelling wheel and means for thrusting

said handles apart in the stroke of the handles in one direction.

3. Rowing mechanism for boats comprising in combination, a propelling wheel, rowing handles pivoted to swing longitudinally of the boat, drive gearing for transforming the oscillatory movement of the rowing handles into rotary movement at the propelling wheel, said handles being separable in simulation of the spreading movement of a pair of oars and stops for limiting the separating and approaching movements of the handles. 55

4. Rowing mechanism for boats comprising a shaft and means for supporting the same transversely of the boat, a ratchet on said shaft, a fork pivoted on the shaft, a pawl mounted on said fork and engaging the ratchet, handles pivoted on opposite sides of the fork to swing toward and away from each other, a spring for yieldingly forcing said handles apart, a propelling wheel and gearing from the ratchet wheel to the propelling wheel. 60

5. Rowing mechanism for boats comprising in combination, a propelling wheel, rowing handles mounted to operate longitudinally of the boat, drive gearing for transforming the back and forth movement of the propelling wheel and means for forcing said handles away from each other during the stroke of both handles in the same direction. 70

6. Rowing mechanism comprising a 80 swinging yoke, handles mounted on said yoke and supporting means for such handles enabling separation and approach of the same in the swinging movements of the yoke in opposite directions in simulation of the spreading movement of the handles of a pair of oars. 85

In witness whereof, I have hereunto set my hand this 20th day of February, 1920.

SUNKER ABAJI BISEY.
